GOLF INSTRUCTION APPARATUS

Andrew D. Sheffer, Brighton, Mich.

Application May 27, 1949, Serial No. 95,775

6 Claims. (CL. 273—35)

1

This invention relates to improvements in golf instruction apparatus, and more particularly to apparatus for artificially controlling or guiding the swing of golf clubs while a golfer is perfecting a swing to obtain the most effective results.

It is among the objects of the invention to provide a golf instruction apparatus of simple and extremely economical construction which can be quickly and easily varied or adjusted to golfers of different heights and for different golf clubs in a set, as some clubs require a different swing from others, which will accurately control the movement of a golf club to produce a swing of the character generally considered the most effective for driving a golf ball, and which does not interfere, in any way, with the movements of the golfer while swinging a club, produces no undesirable confusion or reflexes, and quickly establishes a proper swinging habit so that the golfer will acquire the proper aptitude in swinging the clubs with a minimum amount of practice.

Other objects and advantages will become apparent from a consideration of the following description and the appended claims in conjunction with the accompanying drawings, wherein:

Figure 1 is an elevation of the golf instruction apparatus in operative position;

Figure 2 is a perspective view of a fragmentary portion of the apparatus showing the manner of attaching the apparatus to a conventional golf club;

Figure 3 is a straightened out or development view of the part of the apparatus particularly illustrated in Figure 2;

Figure 4 is a view of another portion of the apparatus, such portion being shown in straightened out condition;

Figure 5 is a diagrammatic view of the apparatus illustrated in Figure 1 with the apparatus slightly modified for a different operating condition than that for which the arrangement shown in Figure 1 is particularly adapted;

Figure 6 is a diagrammatic view similar to Figure 5 showing the apparatus still further modified for a different operating condition; and

Figure 7 is a diagrammatic elevation similar to Figures 5 and 6, but showing the apparatus in a still further modified condition.

With continued reference to the drawings, the apparatus comprises, in general, a vertical post 10 considerably taller than a man, a device 11 mounted on the post near its upper end and providing a line-attaching eye, and a flexible line structure 12 having remote from the post 10 two

2

separate ends attachable to the shank of a conventional golf club 13 near the respectively opposite ends of the golf club shank.

The post 10 may be any suitable structure providing a substantially rigid support for the device 11. It can be an ordinary wooden or metal post, a suitable tree or even the corner of a building, but a suitable wooden post of the proper length is preferred, as this enables the setting up of the apparatus at any desired location.

The device 11 may comprise a staple plate 14 carrying a ring bolt 15 providing an eye for the attachment of the line structure 12 to the post.

The line structure 12 comprises an intermediate portion which may be varied and adjusted in form for different purposes, as will be later explained, but which, in all cases, has two separate ends attachable to the golf club near respectively opposite ends of the shank of the club, and includes split leather thongs 16 connected respectively to the two separate ends of the line structure to connect such ends to the golf club shank. These thongs are particularly illustrated in Figures 2 and 3, and each comprises an elongated strap of suitable material, such as leather, having holes 17 respectively disposed near its open ends and having an elongated slit 18 in its intermediate portion. Each of the thongs is attached to the line structure 12 by inserting the end portion of the line structure through the holes 17 with the strap 16 doubled so that the two holes 17 are in registry with each other, turning the end portion of the line structure backwardly to form a loop and securing this loop by a suitable clip 19.

In applying the thongs 16 to the golf club, each thong is looped to provide a clove hitch formation, the golf club shank is inserted through the eye of such clove hitch and the hitch then tightened on the shank of the club to firmly secure the thong to the shank of the club near the respective end of the latter.

In the arrangement illustrated in Figure 1, the line structure 12 comprises a length of flexible line 20 secured at one end to the ring 15 carried by the post 10, and provided at its opposite end with a ring or loop 21, and a second length of line 22 passed through the ring 21 and having the thongs 16 attached to its opposite ends. This second line 22 has knots 23 therein located at substantially equal distances from the mid-length location of the second line, and the ring 21 receives the second line between the knots 23.

With the golf club 13 secured to the ends of the second line 22 by the thongs 16, the golf

club may be carried through a ball-driving swing and will be guided in this swing by the line structure 12, the club being accurately guided at both ends, so that the swing produced will be in exact conformity with the desired results.

In the arrangement diagrammatically illustrated in Figure 5, the apparatus is exactly the same as that illustrated in Figure 1, except the knots 23 are omitted from the second line 22, thus giving the golfer more freedom of movement between the opposite ends of the golf club. This slightly modified form of apparatus may be used for an intermediate or final stage in the instruction course, or for instructions with a different type of golf club from that illustrated in Figure 1, for example, if the club 13 of Figure 1 is a driver, the club 13' of Figure 5 may be a brassie or one of the irons.

The apparatus illustrated in Figure 6 is exactly the same as that illustrated in Figure 1, except that an equalizing bar 26 has been connected at its mid-length location to the free end of the first line 20. The equalizing bar 26 is a short bar of light weight material, such as wood, and is provided, at its mid-length location, with a hole through which the line 20 extends, the line being secured to the bar by a knot 27 in its end, and with a hole near each end. The second line 22 is passed through the holes near the opposite ends of the equalizing bar so that it is slideable relative to the bar and its portions adjacent the free end of line 20 are spread apart by the bar.

The modified apparatus of Figure 6 may be used for a still different club from the clubs 13 and 13' of Figures 1 and 5, or may be used to accommodate the apparatus to a golfer of a different height from the golfers to which the forms shown in Figures 1 and 5 are particularly well adapted.

In the arrangement shown in Figure 7, the modified line structure 12' comprises a single line passed through the ring bolt 15 and so positioned that the ring bolt is near the mid-length location of the line. This single line is attached at its ends to the shank of a golf club 13' which may be the same club, or a different club from those used with the form of the invention shown in Figures 5 and 6, and the form shown in Figure 7 may also be used by a golfer of a different height from those to which the forms shown in Figures 1, 5 and 6 are particularly well adapted.

This improved instruction apparatus not only guides the head of the golf club in its swinging movements, but also firmly guides the hands of the golfer, and thus more quickly and effectively establishes in the golfer the proper habits or reactions in swinging the club in the approved manner.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. Golf instruction apparatus for teaching a golfer proper club swing habits comprising a vertical post, means secured to said post at a height somewhat greater than the height of a man and providing a line-receiving eye, a line

structure attached to said post by said line-receiving eye and having two separate ends remote from said post, a golf club having a shank and a head at one end and a grip at the other end of said shank, and means connecting said line to the shank of said golf club near respectively opposite ends of the club shank, said line structure comprising a first length of single line attached at one end to said line-fastening eye, a ring attached to the opposite end of said first length of line, and a second length of line extending through said ring for attachment at its ends to a golf club.

2. Golf instruction apparatus for teaching a golfer proper club swing habits comprising a vertical post, means secured to said post at a height somewhat greater than the height of a man and providing a line-fastening eye, a line structure attached to said post by said line-fastening eye and having two separate ends remote from said post, a golf club having a shank and a head at one end and a grip at the other end of said shank, means connecting said line ends to the shank of said golf club near respectively opposite ends of the latter, said line structure comprising a first length of single line attached at one end to said line-fastening eye, a ring attached to the opposite end of said first length of line, and a second length of line extending through said ring for attachment at its ends to a golf club, said second length of line having therein two spaced-apart knots disposed adjacent to and at substantially equal distances from the mid-length location of such second length of line.

3. Golf instruction apparatus for teaching a golfer proper club swing habits comprising a vertical post, means secured to said post at a height somewhat greater than the height of a man and providing a line-fastening eye, a line structure attached to said post and having two separate ends remote from said post, a golf club having a shank and a head at one end and a grip at the other end of said shank, and means connecting said line ends to the shank of said golf club near respectively opposite ends of the latter, said line structure comprising a first length of single line secured at one end to said line-fastening eye, an equalizing bar secured at its mid-length location to said first length of line at the opposite end of the latter, said equalizing bar having a hole adjacent each opposite end thereof and a second line passed through the holes in said equalizing bar and attached at its opposite ends to said shank, one near the head and one near the grip end thereof.

4. Golf instruction apparatus for teaching a golfer proper club swing habits comprising a vertical post, means secured to said post at a height somewhat greater than the height of a man and providing a line-fastening eye, a line structure attached to said post and having two separate ends remote from said post, a golf club including a shank and a head at one end and a grip at the other end of said shank, and means connecting said line ends to the shank of said golf club near respectively opposite ends of the latter, said line structure including a single line extending through said line-fastening eye.

5. Golf instruction apparatus comprising an upright support, a line structure providing two separate ends at one end of said structure, means connecting the other end of said line structure to said support at a height above the ground somewhat greater than the height of a man, a golf club including a shank and a head at one

end and a grip at the other end of said shank, and means connecting said two line ends to said club shank one near the head and one near the grip of said club.

6. Golf instruction apparatus comprising an upright support, a line structure providing two separate ends at one end of said structure, means connecting the other end of said line structure to said support at a height above the ground somewhat greater than the height of a man, a golf club including a shank and a head at one end and a grip at the other end of said shank, and means connecting said two line ends to said club shank one near the head and one near the grip of said club, said line structure being ar-

ranged to provide limited freedom of relative movement between said line ends.

ANDREW D. SHEFFER.
